UNITED STATES PATENT OFFICE.

WILLIAM G. CANFIELD, OF ST. LOUIS, MISSOURI.

FLUID-PRESSURE-OPERATED JACK.

1,297,091.

Specification of Letters Patent. Patented Mar. 11, 1919.

Application filed May 15, 1918. Serial No. 234,747.

To all whom it may concern:

Be it known that I, WILLIAM G. CANFIELD, a citizen of the United States, residing at St. Louis, and State of Missouri, have invented 5 new and useful Improvements in Fluid-Pressure-Operated Jacks, of which the following is a specification.

This invention is an improved fluid pressure operated jack which is especially adapted 10 for use for raising or lowering an automobile or other weight, but which can be used for any analogous purpose, the object of the invention being to provide an improved jack of this character which is simple 15 in construction and which is automatic in operation.

With the above and other objects in view, the invention consists in the construction, combination and arrangement of devices 20 hereinafter described and claimed.

In the accompanying drawings:

Figure 1 is an elevation of a jack constructed and arranged in accordance with my invention and showing the same in raised 25 position.

Fig. 2 is a vertical central sectional view of the same, in raised position.

Fig. 3 is a similar view of the same in lowered or closed position.

Fig. 4 is a horizontal sectional view of the same on the plane indicated by the line 30 4-4 of Fig. 2.

Fig. 5 is an inverted horizontal sectional view of the same on the plane indicated by the line 35 5-5 of Fig. 2.

Fig. 6 is a detail transverse sectional view of the base.

Fig. 7 is a detail sectional view of the valve.

Fig. 8 is a detail perspective view of the prop.

My improved fluid pressure operated jack comprises a plurality of cylindrical sections which are telescopically related so that the 45 jack may be vertically extended or may be lowered. Within the scope of the invention the jack may be provided with any suitable number of such sections but for the purposes of this specification the jack is here 50 shown as comprising a lower section 1, an intermediate section 2 and an upper section 3. The lower section is open at the upper end and has a base 4 at the lower end and which closes the same, the base being screwed 55 on the section 1 as at 5 and being formed with a flange 6 around the section 1, the

said flange having vertical non-circular recesses 7 which are open at the upper end. A pipe 8 for the introduction of compressed air or other motor fluid under compression is 60 arranged in a coil in the bottom of the section 1 and is provided with openings 9, the outer end of the pipe extending radially through the flange 6 and forming a nipple 10 to which a hose leading from a suitable air compressor or other reservoir may be attached. A rod 11 extends across the center of the bottom of the section 1 and has one end screwed in the pipe coil 8 as at 12 the other end of the said rod being arranged in the nipple 10 and screwed into the same as at 13. A stop ring 14 is screwed around the upper end of the section 1.

The section 2 is arranged for vertical telescopic movement in the section 1, is open at 75 the upper end and is closed at the bottom as at 15, said bottom having a central opening 16. A packing disk 17 is secured under the bottom and between the same and a flanged disk 18, said flanged disk being secured to the 80 bottom by rivets 19 which extend through said packing disk and also through the bottom, as shown in Fig. 2. The packing disk and the flanged disk are provided with an opening 20 of greater diameter than the opening 16 and 85 which is concentric therewith.

A valve 21 is provided to close and open the opening 16 and is here shown as having a head 22 which may be seated closely against the bottom 15 and as also having a 90 downwardly extending stem which is provided with a central globular enlargement 23 whereby recesses 24, 25 are provided above and below said globular enlargement. A base 26 is also here shown at the lower 95 end of the valve stem and which is engaged by a link 27 to which the upper end of a valve operating chain 28 is attached, the lower end of said chain being attached near the center of the rod 11. To hold the valve in either opened or closed position, I provide a pair of oppositely and radially arranged locking bolts 29 which pass through and are slidable in openings in guide studs 30 which are here shown as 100 screwed to and depending from the flanged disk 18. Each locking bolt has a gripping yoke 31 at its inner end and is also provided with a coiled spring 32, said springs being arranged between the gripping yokes 105 31 and the guide studs and serve to hold the gripping yokes of the locking bolts engaged 110

with the valve stem either in the recess 24 above or the recess 25 below the globular enlargement 23 and hence said locking bolts and springs serve to hold the valve either in 5 open or in closed position.

When the section 2 has been moved up to the full extent by compressed air in the section 1, the chain 28 then tightens and draws the valve downwardly to open position, the 10 valve uncovering the opening 16 and permitting compressed air to then pass through the lower section 1 into the section 2 and to raise the section 3, as will be understood. When the section 2 reaches a fully lowered 15 position, as shown in Fig. 3, the base 26 of the valve strikes the rod 11 and said valve is then caused to move upwardly relatively to the section 2 and to close the opening 16 and is held in such closed position by the 20 locking bolts 29.

The intermediate section 2 is provided at its upper end with a stop ring 33 which is screwed thereon and which is adapted to engage the upper end of the section 1 when 25 said section 2 is lowered. A tubular casing member 34 has its upper end screwed on the stop ring 33 and is provided at its lower end with an internally arranged stop ring 35 which is screwed thereto and which when 30 the section 2 moves upwardly engages the stop ring 14 and thereby limits the upward movement of said section 2.

The section 3 is closed at the bottom as at 36 and is provided with a packing disk 37 and a disk 38 to hold the same in place, said disks being secured to the bottom by rivets 39. A stop ring 40 is screwed around the upper end of the upper section 3. A tubular casing member 41 has its upper end screwed 40 on the stop ring 40 and is provided with an internally arranged stop ring 42 at a suitable distance from its lower end and which stop ring 42 coacts with a stop ring 43 on the upper end of the casing member 34 to limit the upward movement of the section 3. The vertical length of the casing member 41 exceeds that of the upper section 3 so that when 45 the jack is in lowered or closed position, as shown in Fig. 3, said casing member 41 bears at its lower end directly on the flange 6 of the base 4 and completely houses and incloses 50 all parts of the jack excepting the base and top.

An exterior flange ring 44 is screwed on 55 the upper end of the casing member 41. A cap nut 42 is arranged for rotation in and on the upper end of the upper section 3 and is provided with ball bearings 45, 46 to reduce the friction to the minimum. A top 47 is arranged on the cap nut and has a depending flange wall 48 arranged around the flange ring 44 and also has an interiorly arranged lower flange ring 50 which is screwed in the lower end of said flange wall and which 60 bears under said flange ring 44.

A manually adjustable screw member 51 forms the upper end of the jack and is screwed on the cap nut and is here shown as hollow and having a bottom 52 and cover 53. To prevent the screw member 51 from turning and to permit said member to be moved vertically by turning the cap nut, I provide a pair of standards 54 which have their lower ends secured to the bottom of the member 3 as at 55, said standards passing through 70 openings 56 in a base flange 57 with which the screw member 51 is provided and the said standards having stop heads 58 at their upper ends. To enable the cap nut to be manually rotated for the purpose of adjusting the 80 screw member 51 vertically, I provide the cap nut and also the flange wall 48 of the top 47 with openings 59 in any one of which a radially arranged hand lever 60 may be inserted.

When my improved jack is used for lifting an automobile, it is preferably used in connection with a rack which I have fully described and claimed in a co-pending application for Letters Patent of the United 90 States of even date herewith. The lifting jack may, however, be used independently of the rack and for any suitable purpose.

To support the sections 2 and 3 in raised position without employing compressed air 95 or other motor fluid, I provide props 61 each of which comprises a standard 62 adapted to have its lower end arranged in one of the openings 7 and thereby supported by the base and provided with vertically adjustable 100 arcuate arms 63, 64 which are slidable on the standard and which may be secured to the standard at any desired adjustment by set screws 65. Said arcuate arms may be engaged under the casing members 34 and 41 105 as shown in Fig. 1.

The screw 51 may be adjusted vertically according to the height of the object to be lifted before the jack is employed for lifting the object.

It is thought the operation of the jack will be fully understood from the foregoing description.

While I have herein shown and described a preferred embodiment of my invention, I 115 would have it understood that changes may be made in the form, proportion and construction of the several parts, without departing from the spirit of my invention, and within the scope of the appended claims.

Having thus described my invention, I 120 claim:

1. In a fluid pressure operated jack, a lower section, an intermediate section, and an upper section telescopically related, means 125 to supply motor fluid to the lower section and means controlled by the movement of the intermediate section to supply motor fluid from the lower section to the intermediate section when the latter is raised, and 130

thereby cause the upper section to be also raised.

2. In a fluid pressure operated jack, a cylindrical lower section, a cylindrical intermediate section telescopically fitted in the lower section and having a bottom provided with an opening, a cylindrical upper section telescopically fitted in the intermediate section, a valve carried by the intermediate section and arranged for vertical movement to close and open said opening, an element connecting said valve to the bottom of the lower section and serving to open said valve when said intermediate section is raised, said valve having means to cause the same to be moved to closed position by contacting with the lower section when the intermediate section is lowered, and means to hold said valve in either open or closed position.
- 20 3. In a fluid pressure operated jack, a cylindrical lower section, a cylindrical intermediate section telescopically fitted in the lower section and having a bottom provided with an opening, a cylindrical upper section tele-

scopically fitted in the intermediate section, 25 a valve carried by the intermediate section and arranged for vertical movement to close and open said opening, an element connecting said valve to the bottom of the lower section and serving to open said valve when said intermediate section is raised, said valve having means to cause the same to be moved to closed position by contacting with the lower section when the intermediate section is lowered, means to hold said valve in either 30 open or closed position, said valve holding means comprising a spring projected bolt and said valve having a stem provided with stop recesses either of which may be engaged by said bolt.

4. In a jack of the class described, a plurality of telescopically related cylindrical sections, certain of which are provided with exteriorly arranged casing members, and a prop having means to engage under said casing members for the purpose set forth.

In testimony whereof I affix my signature.
WILLIAM G. CANFIELD.
